UNITED STATES PATENT OFFICE.

OSCAR ALLEN BENJAMIN, OF BONNER SPRINGS, KANSAS.

SHOE-HEEL-SETTING DEVICE.

Application filed August 26, 1926. Serial No. 131,749.

This invention relates to means for attaching wooden heels to women's shoes. These heels have to be nailed from the inside of the shoe and it has always been difficult to get the heel straight on the shoe while it is being nailed for the reason that after glue has been applied to the heel and to the shoe to hold the heel firmly to the shoe, the heel is very liable to slip upon the thin sheet of glue and this makes it almost impossible to hold the heel and the shoe in proper relative positions while the nails are being driven.

The general object of the present invention is to provide a device for holding the heel and shoe in proper relative positions while nails are being driven through the shoe into the heel, and a further object is to provide a heel holding device which is adapted to be clamped either upon a bench or mounted upon the ordinary jack.

Another object is to provide a device of this character having a pocket for the reception of the heel and having a clamping plate shiftable downward into position against the heel portion of the sole of a shoe, the plate and the heel pocket being formed with prongs adapted to penetrate the leather of the shoe and the wood of the heel and to hold the two against relative movement, and a further object in this connection is to provide the heel clamping plate with nailing holes acting as guides for the insertion of the nails.

Still another object is to provide means whereby the shoe supporting members of the attachment may be mounted for rotational movement upon a supporting base so that the attachment may be turned around until proper light has been thrown into the shoe.

Other objects will appear in the course of the following description.

My invention is illustrated in the accompanying drawings wherein:

Figure 1 is a vertical sectional view of a heel setting device for shoes constructed in accordance with my invention;

Fig. 2 is a top plan view of the clamp 10;

Fig. 3 is a top plan view of the turntable;

Fig. 4 is a top plan view of the base, the frame 21 being in section;

Fig. 5 is a top plan view of the foot 27;

Fig. 6 is a top plan view of the socket for the heel;

Fig. 7 is a side elevation of a modified form of supporting base.

Referring to these drawings, it will be seen that in the form of my attachment shown in

Figure 1, 10 designates a bench clamp having the usual shape and formed with the clamp screw 11 passing through the lower jaw 12 of the clamp and carrying a swiveled head 13. The upper jaw of this clamp is formed with a central screw-threaded aperture and the upper face of the jaw has key recesses 14. Disposed upon this upper jaw is a disk 15 having keys 16 adapted to engage in the recesses 14. This disk 15 is centrally apertured for the passage of a central screw.

Mounted upon the disk 15 is the base 17 which supports the heel pocket. This base has a central aperture which is countersunk for the reception of a screw 18, the lower half of which is reduced in diameter and screw-threaded to pass through the central aperture in disk 15 and engage the upper jaw of the clamp 10. Inasmuch as the upper portion of the screw 18 is smooth, it will be obvious that this base 17 may rotate around the screw and over the face of the disk 15. It is held in its adjusted position by means of a lock screw 19 which passes downward through the base 17 and an oil hole 20 is provided whereby oil may be applied to the confronting faces of members 15 and 17.

Extending upward and outward from this base 17 is an arm 21, the upper end of which is provided with the horizontally disposed sleeve 22 and operating through this sleeve is a shank 23. The shank 23 is held in adjusted position within the sleeve 22 by means of the set screw 24. The end of the shank has the screw-threaded collar 25 through which passes the clamping screw 26. The lower end of this screw has swiveled to it the clamping plate 27 in the shape of a heel and formed with a plurality of pairs of nail holes 28, see Figure 5. The under face of this plate 27 has a plurality of prongs 29 designed to be forced down through the insole of the shoe and into the upper end of the wooden heel A.

Attached by screws 30 to the base 17 is the heel pocket 31 which is larger than but has the general shape of a shoe heel and mounted upon the inner face of this pocket are a plurality of leaf springs 32 which engage against four sides of the heel A and act to center this heel. Preferably a felt lining 33 is attached at its upper margin to the pocket or cup 31 and extends down over these springs so as to prevent the springs from marring the heel. The upper face of

the bottom of the pocket is formed with upwardly extending prongs 34 which, when the clamping plate 27 is forced down, engage in the bottom of the heel.

5. While in Figure 1 I have illustrated a bench clamp 10, many shops are not equipped with benches but with the ordinary shoe jacks and for the purpose of mounting my heel clamping device upon 10 such a shoe jack I may provide the plate 15^a which is formed with the centrally disposed, downwardly extending hub portion 35, socketed at 36 to receive the upper end of the stand or jack 37. Otherwise than 15 this, the plate 15^a is formed in the same manner as the plate 15.

In the use of this construction, the heel and insole are glued together and then the heel is disposed within the springs 32 and 20 the clamp screw 26 forced downward, causing the clamping plate 27 to press downward against the insole, the prongs 29 and 34 thus being forced into the heel and holding the heel from any movement with reference to the pocket 31 and holding the shoe against any movement with reference to the heel. The base 17 may now be rotated into any desired position to permit the heel clamping plate 27 to be properly illuminated 25 and then the nails will be driven downward through the apertures 28 to hold the insole and the heel together. Preferably a special countersink will be used having a shank so reduced as to pass freely through the openings 28 so that the nail heads may be forced downward below the surface of the insole. I have illustrated two sets of nailing holes 28 to accommodate larger or smaller heels. By swivelling the plate 27 and the screw 26, 30 the heel plate is adjustable to any heel seat. The adjustment of the shank 23 enables the operator to adjust the machine for different styles of wood heels; securing a uniform pressure all around the heel and making a 35 perfect fit. It will be obvious also that the screw 26 and heel plate 27 secures a much better contact between the glued surfaces of the heel and shoe than is possible where the heel and shoe are pressed together by hand.

50. I claim:

1. A heel setting device comprising a base carrying a heel pocket, the pocket being formed with a plurality of leaf springs acting to center a heel within the pocket, and 55 the bottom of the pocket having upwardly projecting prongs, a plunger screw mounted above the base in approximate line with said pocket and carrying a swiveled plate at its lower end formed with prongs.

60. 2. A heel setting device comprising a base carrying a heel pocket, the pocket being formed with a plurality of leaf springs acting to center a heel within the pocket, and 65 the bottom of the pocket having upwardly projecting prongs, a plunger screw mounted

above the base in approximate line with said pocket and carrying a swiveled plate at its lower end formed with prongs, said plate having a plurality of nailing apertures.

3. A heel setting attachment comprising a support, a base rotatably mounted upon the support for rotation in a horizontal plane and having an upwardly extending arm, and an upwardly opening heel pocket mounted upon the base with its axis in line with the axis of rotation of the base, a plunger screw operatively supported by said arm above the heel pocket and carrying a swiveled heel plate at its lower end formed with nailing apertures.

4. A heel setting attachment for shoes comprising a supporting member, a base rotatably mounted upon the supporting member and having an upwardly extending arm formed with a horizontal sleeve, a shank adjustable horizontally through said sleeve, a screw-threaded plunger carried by the end of the shank and extending downward toward the base and carrying a swiveled heel plate, and a heel pocket mounted upon the base beneath said plunger and having upwardly extending prongs in its bottom.

5. A heel setting attachment for shoes comprising a supporting member, a base rotatably mounted upon the supporting member and having an upwardly extending arm formed with a horizontal sleeve, a shank adjustable horizontally through said sleeve, a screw-threaded plunger carried by the end of the shank and extending downward toward the base and carrying a swiveled heel plate, and a heel pocket mounted upon the base beneath said plunger and having upwardly extending prongs in its bottom, springs attached at their upper ends to the walls of said pocket and adapted to center the heel therein, and a lining covering said springs.

6. A heel setting attachment comprising a supporting member adapted to be mounted upon a support and having a centrally screw-threaded aperture, a plate mounted upon the supporting member and having a corresponding screw-threaded aperture, a base mounted upon the plate, a screw passing through the base and through the screw-threaded apertures of the plate and supporting member, the base being thus rotatably mounted upon the plate, said base having an upwardly extending arm, a lock screw passing through the base and holding it in any one rotatably adjusted position, a heel pocket mounted upon the base and adapted to receive the heel of a shoe, a screw-threaded plunger operatively mounted upon said arm and having a swiveled heel plate at its lower end, the heel pocket having centering means for the heel.

7. In a heel setting attachment, a base having a heel pocket and provided with an up-

- wardly extending arm, a horizontally disposed arm shiftable upon the first named arm, means for holding the second named arm in adjusted positions, the extremity of the second named arm having a vertical screw-threaded portion, and a plunger having screw-threaded engagement with the last named portion and confronting said heel pocket.
- 10 8. A heel setting device comprising a base carrying a heel pocket, the pocket being formed with a plurality of leaf springs acting to center the heel within the pocket, and a plunger mounted above the pocket in approximate line therewith and carrying a plate at its lower end adapted to engage the heel and hold it in the pocket.
9. A heel setting device for shoes comprising a horizontal base having an upwardly extending arm and a heel pocket, a support upon which the base is rotatably mounted for movement in a horizontal plane, and a plunger mounted upon said arm above the pocket and having a heel plate, the base, the plunger and the heel plate being disposed in approximately vertical alignment.
10. A heel setting device for shoes comprising a base having an upwardly extending arm formed with a horizontal sleeve, a shank adjustable horizontally through said sleeve, a plunger carried by the end of the shank and extending downward toward the base, and a heel pocket mounted upon the base beneath said plunger.
- 35 11. A heel setting device for shoes comprising a base having an upwardly extend-
- ing arm formed with a horizontal sleeve, a shank adjustable horizontally through said sleeve, a plunger carried by the end of the shank and extending downward toward the base, and a heel pocket mounted upon the base beneath said plunger, the heel pocket being formed with resilient means for centering a heel therein.
12. A heel setting device for shoes comprising a base having an upwardly extending arm and a heel pocket mounted upon the base, an adjustable member carried by the upper end of the arm and a vertical screw-threaded plunger mounted upon the member above the pocket and having a heel plate perforated for the passage of brads, the member being adjustable upon the arm to thereby center the plunger with relation to the heel of the shoe.
13. A heel setting device for shoes comprising a base having an upwardly extending arm and a heel pocket mounted upon the base, a support for the base upon which the base is rotatable, means for holding the base set in any rotatably adjustable position, a member adjustably mounted upon the upper end of the arm, and a vertical screw-threaded plunger mounted upon said member above the pocket and having a heel plate perforated for the passage of brads, the member being adjustable to thereby center the plunger with relation to the heel of the shoe.

In testimony whereof I hereunto affix my signature.

OSCAR ALLEN BENJAMIN.
